UNITED STATES PATENT OFFICE

93,121

DESIGN FOR AN OUTBOARD MOTOR

Walter C. Miller, South Bend, Ind., assignor to
Johnson Motor Company, Waukegan, Ill., a
corporation of Delaware

Application April 9, 1934, Serial No. 51,353

Term of patent 7 years

To all whom it may concern:

Be it known that I, WALTER C. MILLER, a citizen of the United States, residing at South Bend, in the county of St. Joseph and State of Indiana, have invented a new, original, and ornamental Design for Outboard Motor, of which the following is a specification, reference being had to the accompanying drawing, forming part thereof.

In the drawing:

Fig. 1 is a side elevation of an outboard motor

showing the design in accordance with this invention;

Fig. 2 is a rear elevation of the outboard motor; and

Fig. 3 is a top plan view thereof.

I claim:

The ornamental design for an outboard motor as shown.

WALTER C. MILLER.
